UNITED STATES PATENT OFFICE.

HENRY C. HERR, OF PITTSBURGH, PENNSYLVANIA, ASSIGNOR, BY MESNE ASSIGNMENTS, TO SOUTH SIDE TRUST COMPANY, TRUSTEE, OF PITTSBURGH, PENNSYLVANIA, A CORPORATION OF PENNSYLVANIA.

METHOD OF EXPANDING STRANDED SHEET METAL.

1,231,888.

Specification of Letters Patent.

Patented July 3, 1917.

Application filed August 29, 1913. Serial No. 787,388.

To all whom it may concern:

Be it known that I, HENRY C. HERR, a citizen of the United States of America, residing at Pittsburgh, in the county of Allegheny and State of Pennsylvania, have invented certain new and useful Improvements in Methods for Expanding Stranded Sheet Metal, of which the following is a specification, reference being had therein to the accompanying drawings.

The invention relates to the manufacture of expanded sheet metal, and has particular reference to the novel method of expanding a stranded sheet, as hereinafter set forth.

15 In the drawings:

Figure 1 is a plan view of the stranded sheet, showing the manner of slitting and expanding the same;

Fig. 2 is a cross section through the stranded sheet in engagement with the expanding device;

Fig. 3 is a longitudinal section, illustrating one step in the expanding operation;

Fig. 4 is a diagrammatic view of the sheet, showing the successive operations in expanding the same;

Fig. 5 is a plan view of a fragment of the completed product;

Fig. 6 is a similar view of a modified construction; and

Fig. 7 is a cross section thereof.

In the art of expanding sheet metal as usually practised, an incident of the lateral expansion of the sheet is the longitudinal contraction thereof; but this result is not objectionable in the production of expanded metal for ordinary purposes. For special purposes, however, it is desirable to expand only a portion of the original blank, and where this is done difficulty is experienced in preventing the buckling of the unexpanded portion, due to the longitudinal contraction of the expanded portion. Such a result may be avoided by the elongation of the strands to compensate for their lateral deflection; but a new difficulty results from this—viz., the weakening of the structure adjacent to the division line between the expanded and unexpanded portions.

The present invention is designed to overcome this difficulty by differentially expanding the stranded sheet, and the invention consists, first, in the method of producing a progressive or differential expansion; and second, in the production of this result by successive step-by-step expansion of different portions of the sheet.

In detail, A is a sheet metal blank, which is stranded, preferably, by first slitting with aligned bonds B, and then re-slitting centrally of the strands to produce staggered bonds B', the opposite margins D of the blank being left unslitted. As an incident of the stranding operation, the sheet is bent to deflect alternate strands into different planes, as shown at C and C' in Fig. 2. The expansion of the stranded sheet is accomplished by a series of successive operations, which produce after each partial expansion an elongation of the strands, permitting of further expansion without contraction of the unexpanded portion. As shown in Fig. 3 the stranded sheet after each partial expansion and before each elongation contracts longitudinally and consequently bows. Furthermore, these successive operations are so conducted that the sheet is expanded differentially, the greatest expansion being in the center of the sheet, or at the point farthest removed from the unexpanded portion, while the least expansion is immediately adjacent to the unexpanded portion.

As shown in Fig. 1, the primary expansion of the sheet is effected by drawing the opposite edges thereof in opposite directions, as for instance by engaging said edges of the sheet with grippers E secured to traveling chains F, which travel in divergent planes. It is necessary, however, to prevent the overstraining of the portions of the blank adjacent to the unslitted margins D thereof, and this is preferably accomplished by engaging guides G and H with one line of strands a short distance from the margin. These guides are arranged to extend parallel to the direction of travel of the chains F, and thus the initial expansion is confined to the portion of the stranded blank between

said guides and does not extend to the portions between the guides and the unstranded margins.

After this first expanding step, the portion of the blank thus expanded is operated upon to elongate the strands thereof, so as to permit of further expansion, this elongation being preferably accomplished by passing between rolls I. At the same time, the grippers E continue to draw the margins of the sheet in opposite directions, and the guides G and H being omitted, the expansion will primarily take place in that portion of the stranded sheet not previously expanded. This is for the reason that the rolls I tend to hold the central portion of the sheet from lateral movement, but the expansion is not confined to the portions outside of the rolls but extends also into the central portions, the total result being a differential expansion, progressively increasing in the direction from the margin toward the center.

The alternate operations of expanding the central and marginal portions of the sheet continue until the full degree of expansion is attained, after which the sheet is passed through crowned rolls J, which harmonize the thickness of the sheet to the differential expansion thereof and deliver it in flattened condition. The product is illustrated in Fig. 7, and as indicated, is progressively expanded from the margin to the center.

By expanding sheet metal in the manner described, the overstressing of any portion of the blank is avoided, and furthermore the product obtained is one which is free from all of the defects common to expanded sheets which has unexpanded portions. This is for the reason that there is no sudden change in either the direction or the gage of the strands, and consequently a weak line in the sheet is avoided. A still greater strength is obtained by progressively changing the width of the strands, with the widest strands nearest the unstranded portion, as shown in Fig. 6.

I claim—

1. The method of expanding stranded sheet metal, comprising the constant expansion of a sheet, and the successive expansion of constituent portions of said sheet.

2. The method of expanding sheet metal, comprising the constant separation of opposite margins of a stranded sheet, and the differential elongation of the strands to form a progressive expansion.

3. The method of expanding sheet metal, comprising the successive lateral expansion of portions of a stranded sheet, and the elongation of the strands of one portion during the interval in which they are not laterally expanded.

4. The method of expanding sheet metal,

comprising the constant lateral expansion 65 of a stranded sheet, with successive lateral expansion of constituent portions thereof, and the elongation of the strands of one portion during the interval in which they are not laterally expanded. 70

5. The method of forming expanded metal, comprising the differential stranding of the sheet and subsequent constant lateral expansion of said sheet, with successive expansion of constituent portions thereof and 75 elongation of the strands.

6. The method of expanding sheet metal, comprising the forming of a sheet with stranded and unstranded portions, and the subsequent expansion of the stranded portion of said sheet progressively from the unstranded portions thereof. 80

7. The method of expanding metal, comprising the drawing apart of opposite edges of a stranded sheet, and the successive holding of constituent portions of said sheet from lateral expansion. 85

8. The method of expanding sheet metal, comprising the constant separation of opposite edges of a stranded sheet, and the 90 intermittent rolling of a portion of said sheet to elongate the strands thereof.

9. The method of expanding sheet metal, comprising the constant drawing apart of unstranded margins of a stranded sheet, the 95 intermittent guiding of the stranded portion of said sheet to confine the expansion to a portion thereof, and the successive rolling of said portion to elongate the strands thereof, and to confine the lateral expansion 100 to another portion of the sheet.

10. The method of expanding sheet metal, comprising the differential lateral expansion of a stranded sheet, and the differential thinning and elongation of the strands of 105 the sheet to compensate for said differential expansion.

11. The method of expanding sheet metal, comprising the differential lateral expansion of a stranded sheet, and the corresponding differential thinning and elongation of the strands to compensate for the differential expansion without longitudinal contraction. 110

12. The method of expanding sheet metal, comprising the differential and progressive lateral expansion of a stranded sheet, and the corresponding differential and progressive thinning and elongation of the strands 115 to compensate for said differential expansion. 120

13. The method of expanding sheet metal, comprising the alternate and differential lateral expansion of different portions of a stranded sheet, and the differential rolling 125 of the expanded sheet to harmonize and equalize the differential expansion thereof.

14. The method of expanding sheet metal,

comprising the subjection of a stranded sheet to a differential lateral expansion, and the rolling of the sheet by crowned rolls to harmonize the differential expansion thereof.

5 15. The method of forming expanded sheet metal, comprising slitting a sheet to strands of progressively diminishing width and differentially expanding said sheet pro-

gressively from the wide to the narrow strand thereof.

In testimony whereof I affix my signature
in presence of two witnesses.
